UNITED STATES PATENT OFFICE

119,736

DESIGN FOR A FOOD PLATTER OR THE LIKE

Alice V. Brown, Philadelphia, Pa.

Application January 25, 1940, Serial No. 89,694

Term of patent 7 years

To all whom it may concern:

Be it known that I, Alice V. Brown, a citizen of the United States, residing at Philadelphia, in the county of Philadelphia and State of Pennsylvania, have invented a new, original, and ornamental Design for a Food Platter or the like, of which the following is a specification, reference being had to the accompanying drawing, forming part thereof.

Figure 3 is a bottom plan view, and
of Figure 1, of a food platter or the like showing my new design.

I claim:

The ornamental design for a food platter or
the like, as shown.

ALICE V. BROWN.
